RESISTOR HOUSING OR SIMILAR ARTICLE

Eugene A. Blake and Darwin L. Rakowsky, Columbus,
Nebr., assignors to Dale Electronics, Inc., Columbus,
Nebr., a corporation of Nebraska

Filed July 3, 1963, Ser. No. 75,651

Term of patent 14 years

(Cl. D26—1)

Fig. 20

FIGURE 1 is a top perspective view of a resistor housing or similar article showing our new design wherein the body is elongated with a substantially narrow top and the outer edges of the elongated ribs are substantially square;

FIGURE 2 is an end elevation thereof of the two identical ends of the design of FIGURE 1;

FIGURE 3 is a top plan view of the unit shown in FIGURE 1;

FIGURE 4 is a side elevation thereof as seen from the left of the unit shown in FIGURE 1;

FIGURE 5 is a top perspective view of a resistor housing or similar article showing our new design wherein the body is shortened with a substantially wide top and the outer edges of the elongated ribs are substantially square;

FIGURE 6 is an end elevation thereof of the two identical ends of the design of FIGURE 5;

FIGURE 7 is a side elevation thereof as seen from the left of the unit in FIGURE 5;

FIGURE 8 is a top plan view of the unit shown in FIGURE 5;

FIGURE 9 is a top perspective view of a resistor housing or similar article showing our new design wherein the body is shortened, the upper side portions of the body curve inwardly and upwardly toward a narrower top and the outer edges of the elongated ribs are substantially square;

FIGURE 10 is an end elevation thereof of the two identical ends of the design of FIGURE 9;

FIGURE 11 is a side elevation thereof as seen from the left of the unit in FIGURE 9;

FIGURE 12 is a top plan view of the unit shown in FIGURE 9;

FIGURE 13 is a top perspective view of a resistor housing or similar article showing our new design wherein the body is shortened, the upper side portions of the body curve inwardly and upwardly toward a narrower top and the elongated ribs are rounded to create the appearance of a sine curve at the end elevations of the body;

FIGURE 14 is an end elevation thereof of the two identical ends of the design of FIGURE 13;

FIGURE 15 is a side elevation thereof as seen from the left of the unit in FIGURE 13;

FIGURE 16 is a top plan view of the unit shown in FIGURE 13;

FIGURE 17 is a top perspective view of a resistor housing or similar article showing our new design wherein the body is shortened, the upper side portions of the body curve inwardly and upwardly toward a narrower top and the elongated ribs are rounded to a semi-circular shape;

FIGURE 18 is an end elevation thereof of the two identical ends of the design of FIGURE 17;

FIGURE 19 is a side elevation thereof as seen from the left of the unit in FIGURE 17; and

FIGURE 20 is a top plan view of the unit shown in FIGURE 17.

The dominant features of our new design reside in the portions shown in solid lines and the common features of the five illustrated embodiments of our new design consist primarily in the elongated horizontal rib formations on the sides of the body separated at the top of the body by a substantially smooth top portion.

The drawing figures are diagonally lined to indicate shiny surfaces.

We claim:

The ornamental design for a resistor housing or similar article, substantially as described and shown.
